UNITED STATES PATENT OFFICE.

WALTER T. STALL, OF BROCKTON, MASSACHUSETTS, ASSIGNOR TO HIMSELF AND CHARLES H. DEAN, COPARTNERS, DOING BUSINESS AS STALL & DEAN MANUFACTURING COMPANY, OF BROCKTON, MASSACHUSETTS.

THIGH GUARD.

Application filed May 12, 1922. Serial No. 560,374.

To all whom it may concern:

Be it known that I, WALTER T. STALL, a citizen of the United States, residing at Brockton, in the county of Plymouth and 5 State of Massachusetts, have invented new and useful Improvements in Thigh Guards, of which the following is a specification.

This invention relates to thigh guards adapted for use on trousers worn by players 10 of athletic games, to protect the thighs or other portions of the legs.

It is desirable to make guards of this character from indurated sheet fiber, the specific gravity, rigidity and density of this 15 material being such that a relatively thick sheet may be employed, adapted to resist violent shocks and blows without being indented and punctured, and without objectionably weighting the player.

20 A guard possessing a maximum degree of efficiency should be made in a single trough-shaped piece, molded to present a reentrantly curved inner side, conforming approximately to the external shape of the 25 portion of the wearer's leg or thigh, protected by the guard, and a saliently curved outer side.

A single piece fiber guard molded to a trough shape, having plain surfaces, is liable 30 to be warped, or distorted from its predetermined form, and become approximately flat. In other words, it is not sure to retain the desired transverse curvature. I overcome this liability by providing the 35 guard with parallel corrugations, occupying the major portions of the guard, and rendering the predetermined trough-shape permanent. To provide at the marginal portion of the inner side of the guard a 40 surface free from the protuberances formed by the corrugations, and adapted to conform closely to the marginal portion of the surface protected by the guard, I space the corrugations inward from the margin of 45 the guard, in such manner as to provide a continuous plain-surfaced, marginal portion surrounding the corrugated area, and forming a rim or seat, to which may be stitched a cushioning strip of felt bearing 50 on the inner side of the marginal portion of the guard. By "plain surfaced" I mean devoid of corrugations, and having the curvature which the entire side surfaces of the trough-shaped guard would have pos-

sessed if the corrugations had not been 55 formed.

The corrugations extend crosswise of the guard between the longitudinal edges thereof so that each corrugation has a longitudinal curvature conforming to the lateral 60 curvature of the trough-shaped guard, and is, therefore, arched. The arched corrugations impart greater rigidity and permanence of form to the guard than would be the case if the corrugations were substantially 65 parallel with the longitudinal edges of the trough-shaped guard, in which case the guard would be liable to distortion and to become flattened by warping, which is not possible when the corrugations extend 70 crosswise.

Of the accompanying drawings forming a part of this specification,—

Figure 1 is a front elevation of a thigh 75 guard embodying the invention.

Figure 2 is a section on line 2—2 of Figure 1.

Figure 3 is a section on line 3—3 of Figure 1.

The same reference characters indicate 80 the same parts in all of the figures.

My improved guard is made by molding an oblong plate of sheet material, such as vulcanized or indurated fiber to arch the guard between its longitudinal edges which 85 are substantially straight and at right angles with the corrugations. The guard is therefore arched between its longitudinal edges to form a salient outer side and a reentrant inner side. The guard is embossed to form 90 arched parallel corrugations 12, extending crosswise between the longitudinal edges. The corrugations occupy the major portion 95 of the area, and are preferably within the margin of the guard, so that a plain surfaced marginal portion 13 is provided entirely surrounding the corrugations, and constituting a seat or rim to which a felt cushioning strip 14 may be attached, as by 100 stitches 15, engaged with the portion 13. The reentrant inner side of the portion 13 enables said inner side to conform more closely than the corrugated portion, to the portion of a leg or thigh on which the guard 105 is placed.

I find that by arranging the corrugations transversely or crosswise of the longitudinal axis of the guard, so that they are

arched, the effectiveness of the corrugations as a stiffening and form-retaining means is greater, than when they extend lengthwise, or parallel with the longitudinal axis, the 5 fact being that a transversely corrugated trough-shaped guard can be distorted or bent from its predetermined form only with great difficulty, and by the application of greater force than any to which the guard 10 is ever subjected when in use, and that the guard cannot lose its predetermined form by warping.

I do not limit myself to the plain surfaced marginal portion 18, surrounding the 15 corrugations, although I prefer the same. If desired, the corrugations may extend to the margin of the guard, in which case the two longitudinal edges of the guard will be corrugated.

20 I claim:

1. A trough-shaped thigh guard of fibrous

sheet material, arched between its longitudinal edges to form a salient outer side and a reentrant inner side, and provided with arched parallel corrugations extending in 25 the direction of the curvature of the arch, whereby the arched form of the guard is rendered permanent, said reentrant inner side being formed by alternating arched ridges and depressions, and conforming approximately to the surface protected by the guard.

2. A trough-shaped thigh guard substantially as specified by claim 1, the said parallel corrugations being surrounded by a 35 continuous plain surfaced marginal portion, conforming closely to the marginal portion of the surface protected by the guard.

In testimony whereof I have affixed my signature.

WALTER T. STALL.
